UNITED STATES PATENT OFFICE.

FRANK T. KASSEL, OF KANSAS CITY, KANSAS.

DESIGN FOR JEWELRY—NAMELY, A CHARM, PIN, CUFF-BUTTON, OR ARTICLE OF SIMILAR NATURE.

60,040.

Specification for Design.

Patented Dec. 20, 1921.

Application filed April 11, 1921. Serial No. 460,498. Term of patent 3½ years.

To all whom it may concern:

Be it known that I, FRANK T. KASSEL, a citizen of the United States, residing at Kansas City, Wyandotte county, Kansas, have invented a new, original, and ornamental Design for Jewelry—namely, Charms, Pins, Cuff-Buttons, or Articles of Similar Nature, of which the following is a specification, reference being had to the accompanying drawing, forming a part thereof.

In the drawing:

Figure 1, illustrates a face view of a pin embodying the invention.

Fig. 2, is a top edge view of the same.

I claim:

The ornamental design for jewelry, namely a charm, pin, cuff button, or article of similar nature, as shown.

FRANK T. KASSEL.
